United States Patent Office

Des. 191,175
Patented Aug. 22, 1961

191,175

CONSTRUCTION SET ELEMENT

John H. Wright, Evanston, and Carl V. Ohlson, Deerfield, Ill., assignors to A. G. Spalding & Bros. Inc., Chicopee, Mass., a corporation of Delaware

Filed Feb. 18, 1959, Ser. No. 54,666

Term of patent 14 years

(Cl. D34—15)

FIGURE 1 is a perspective view illustrating a construction set element showing our new design as part of a typical model building. The broken line showing of a building is for illustrative purposes only.

FIG. 2 is a front perspective view of the construction set element; and

FIG. 3 is a rear perspective view of the construction set element.

We claim:

The ornamental design for a construction set element, as shown and described.
